UNITED STATES PATENT OFFICE.

RUDOLPH PAVELLA, OF BROOKLYN, NEW YORK.

MECHANISM FOR OPERATING HOISTWAY DOORS.

Application filed October 5, 1923. Serial No. 666,863.

To all whom it may concern:

Be it known that I, RUDOLPH PAVELLA, a citizen of the United States, residing at Brooklyn, in the county of Kings and State 5 of New York, have invented new and useful Improvements in Mechanism for Operating Hoistway Doors, of which the following is a specification.

This invention relates essentially to devices for opening hoistway doors which normally close horizontally over an opening in a sidewalk leading to a basement or cellar.

An object of the invention is to provide vertically movable means entirely independent of the door opening devices for swinging the doors upward to uncover the opening communicating with the basement.

Another object of the invention is to provide a fixed stop, adapted to be engaged 20 when the doors are opened, by a depending member on a rear gate secured to a door to limit the swing of the doors so that when the opening force is moved out of action the doors will gravitate to securely close the 25 opening.

Another object of the invention is to link one of the doors with a rear gate so that when the force is applied directly to one of the doors both doors will open in unison, and 30 when the force is removed by lowering the vertically movable means the doors will simultaneously close.

Another object of the invention is to provide end gates to guard the space between 35 the front ends of the doors, and means secured to the doors or gates to limit the inward swing of the gates.

The invention resides more particularly in the novel combinations hereinafter described and claimed, reference being made 40 to the accompanying drawings in which:—

Fig. 1 represents a perspective view of a device embodying this invention.

Fig. 2 is a horizontal section taken along 45 the line 2 2 of Fig. 1.

Fig. 3 is a vertical transverse section taken along line 3 3 of Fig. 2.

Fig. 4 is a similar section showing the doors in a different position.

50 In the drawings the numeral 5 designates a sidewalk and 6 is the wall of a building. The sidewalk has an opening framed by a rim 7 flush with the sidewalk and having a downwardly extending flange set in the opening. On the frame is swingingly

mounted a pair of doors 8 and 9 to normally close the opening.

The device for opening the doors in unison when force is applied includes: a rear gate or guard 10 secured to the door 9 thus moving therewith. The gate is practically rectangular and it has a depending member 11, the function of which will be hereinafter described. A second gate 12 has one end pivoted at 14 to the door 8 near its forward end while another portion of the gate is pivoted at 15 to the lower portion of the gate 10. The gates overlap each other so that one can pass the other when the doors are actuated. The doors are counterbalanced by means of a weight 16 suspended from one end of a cable 17 guided over rollers 18 and having its other end fastened to the depending portion of the gate.

In order to limit the swing of the doors when opened a stop 19 best seen in Fig. 1, is provided. The stop is secured to the frame and when the doors are fully opened the depending portion of the gate strikes the stop thereby positioning the doors at right angles to the sidewalk or opening so that when the force is removed the doors will automatically swing downward to cover the opening.

The means for raising the doors consists 85 of a post 20 slidably mounted in a hanger 21 fixed to the wall of the hoistway. The upper end of the post has a jib or projecting arm 22 and a cable guided over rollers 24 operated by a winch or similar well-known 90 means, not shown, is employed to raise ash barrels and other articles from the basement. The post can be vertically raised and lowered in any well-known way. On the crane post is mounted a pair of anti-friction rollers 95 25 at times made to coact with a cam block 26 fixed to the bottom of the door 8. The rollers ride over the cam transmitting the initial thrust or push to open the doors. A rod 27 is yoked to the post by means of a 100 head member 28 and it carries an anti-friction roller 29 to at times engage the cam.

To prevent anybody from accidentally falling into the basement through the front gap between the open doors a pair of gates 105 30 swingingly connected by means of spring hinges to the doors are employed. The gates can be swung outwardly to give passage to the hoisted articles. As indicated in Fig. 2 the gates are prevented from swinging in-

wardly by angle irons 31 secured to the front inner end of each door or gate or forming a part of the hinge. The gates are out of line with each other so that when the doors close they can pass each other or in other words one overlaps the other.

When it is desired to open the doors the post is operated to vertically slide in the hanger. The anti-friction rollers on the post roll over the cam which actuates the rear pivoted gate link connection to swing both of the doors upward. In this position the doors are held open by the engagement of the side of the rod with the cam, as indicated in Fig. 3.

The crane when coacting with the door is raised above the level of the sidewalk or above the plane of the doors when closed and the jib can be swiveled with the post as fulcrum to bring it in any desirable position to hoist or unload the articles. It will be seen that the post is arranged at the front of the hatchway and the means for opening both doors in unison at the extreme back of the hatchway.

Modifications of the invention may be made within the scope of the claims and the law of equivalents for example, when the opening is located adjacent a wall the rear closure can be omitted and the gate 12 can be in the form of a link with one end pivoted to one of the doors and the other end to a bracket or arm fixed to the other door.

I claim:

35. 1. In mechanism for operating hoistway doors the combination with a pair of swinging doors made to close horizontally over an opening, of a member secured to one of the doors, means for pivotally connecting the 40 other door to the member, a fixed stop at times engaged by the member to limit the opening movement of the doors, and a verti-

cally movable post coacting with the bottom of one of the doors to force both of the doors open.

45. 2. In mechanism for operating hoistway doors the combination with a pair of swinging doors made to close horizontally over an opening, of a gate secured to one of the doors, a second gate pivotally connected to the other door and the first named gate, a fixed stop on the secured gate to limit the opening movement of the doors, and a vertically movable post coacting with the bottom of one of the doors to force both of the 55 doors open.

60. 3. In operating hoistway doors the combination with a pair of swinging doors made to close horizontally over an opening, of a gate secured to one of the doors, a depending member located at the lower end of the gate pivotally, a second gate connected to the other door and pivoted to the first named gate, a fixed stop at times engaged by the depending member to limit the opening movement of the doors, and a vertically movable post coacting with the bottom of one of the doors to force both of the doors open.

65. 4. In mechanism for operating hoistway doors the combination with a pair of swinging doors made to close horizontally over an opening, of a pair of gates hinged to the doors to protect the opening, one overlapping the other, and a stop secured to the 70 doors to prevent inward swing of the gates when the doors are open.

75. In testimony whereof I have hereunto set my hand in the presence of two subscribing witnesses.

RUDOLPH PAVELLA.
